United States Patent Office

Des. 208,836
Patented Oct. 3, 1967

208,836

DREDGE OR THE LIKE

David R. Talbott, 224 Westwood Road,
Annapolis, Md. 21401

Filed Oct. 31, 1966, Ser. No. 4,482

Term of patent 14 years

(Cl. D71—1)

Fig. 1

Fig. 2

Fig. 3

FIG. 1 is a side perspective view of a dredge or the like showing my new design;

FIG. 2 is a front perspective view of the dredge or the like; and

FIG. 3 is a rear perspective view of the dredge or the like.

The dominant features of my design reside in the portions shown in full lines.

I claim:

The ornamental design for a dredge or the like, as shown and described.
